CONTAINER

Lydia B. Koch, New York, N. Y.

Application September 17, 1935, Serial No. 40,888

1 Claim. (Cl. 229—4.5)

The principal objects which the present invention has in view are:—to be enabled through utilization of two strips of material to shape the same to simulate an improved milk bottle and the like; to be enabled to make containers of various shapes; to provide means to reduce to a minimum leakage of liquids through the bottom of the completed containers; to be enabled to manufacture the containers in a single operation; to be enabled to ship various shaped containers in a common carton and to utilize minimum space; to secure simplicity of construction and operation in the manufacture of the containers; and to obtain other advantages and results as may be brought out in the following description.

In the drawings:—

Figure 1 is a schematic view showing the initial relation of flat sheet blanks from which the container is constructed;

Figure 2 is a side elevational view of the container partially completed;

Figure 3 is a vertical sectional view of the same shown as taken on the line 3—3 of Figure 2;

Figure 4 is a similar view and showing the upper part of the container in completed condition;

Figures 5 and 7 are similar views and showing the lower part of the container shaped to embody features of the present invention with Figure 5 shown as taken on the line 5—5 of Figure 6;

Figures 6 and 8 are top and bottom plan views of the same;

Figure 9 is an enlarged fragmentary sectional view of the lower part of the container wherein features of the present invention are shown in detail and taken on line 9—9 of Figure 6;

Figure 10 is an enlarged transverse sectional view shown as taken on the line 10—10 of Figure 7;

Figures 11 and 12 are enlarged side elevational views of the completed container, Figure 12 being shown as of a slightly different construction; and

Figure 13 is a plan of a shipping container and showing containers constructed in accordance with the present invention packed therein.

As will be seen in the drawings, and referring to Figure 1, the present invention is more particularly directed to construction of containers, such as bottles and the like to simulate the appearance and purpose of a conventional milk bottle, and to be manufactured of various shapes and sizes. Having this in mind, there are two blanks of sheet metal or paper. The blank indicated by the numeral 15 is arcuate in form constituting a segment of an annular strip. The edges 16 and 17 of said blank 15 are concentric.

Adjacent the edge 17 is an area 18 provided with an adhesive.

The other blank 19 is an elongated rectangular sheet, the longitudinal margins or edges 20 and 21 whereof are parallel. The length of the sheet 19 at the edge 20 thereof is equal to the length of the longer arcuate edge 17 of the first mentioned blank 15. Both the top and bottom margins 20 and 21 of blank 19 are provided with an adhesive thereon as indicated at 22 and 23 respectively. The upper strip of adhesive 22 preferably only extends half the length of the blank, in view of the fact that the blank is, in the present disclosure, of sufficient length to wrap twice about a mandrel and thus bring the adhesive between the two plies of material and leave the inside face of the bottle clear of any adhesive. It may here be noted that the material comprising blanks 15 and 19, if paper, is preferably a prepared moisture-proof paper, especially when the completed bottle is to be used for liquids.

With the two blanks 15 and 19 formed as shown, the marginal area next the longer arcuate edge 17 of the upper blank 15 is overlapped upon the marginal edge next to the upper long edge 20 of the lower blank 19, and the two blanks then folded around a mandrel, the lapping margins having adhesive therebetween and being forced into juxtaposition, pressed one upon the other and caused to tenaciously adhere forming the sections into the body portion of the bottle.

While the specific structure of this body portion of the bottle has been shown, and therefore described, as composed of two sections secured together, it will be understood that the invention is not limited to this specific formation or number of parts, as the body portion may as well be made of one piece and on the other hand may be made of more than two pieces. In any event, the overlapping vertical ends of the blank or blanks are secured by vertical strips of adhesive 24 to both keep the blanks from unwinding and for sealing the vertical seam against egress of the contents of the bottle.

An important feature of the present invention resides in the fact that the body portion of the bottle is made, in cross-section, of an appropriate shape enabling a plurality of bottles to be placed side by side, for instance in a shipping container C, with a minimum of waste space between the bottles. In Figures 5 to 10, and at the left of Figure 13, as designated by character A, bottles have been illustrated which are substantially triangular in cross-section, having rounded vertical edges, whereas Figures 11 and 12, and the right

hand side of Figure 13 as designated by character B, illustrate bottles which are rectangular in cross-section, these also having rounded vertical corners. The invention is not limited to these specifically selected shapes, but other cross-sectional shapes which will be conducive to close packing and minimum waste space may be substituted.

A further important feature of the present invention resides in the formation of the bottom of the container and in the means and method of forming and connecting the bottom wall with the peripheral or side wall of the body portion of the bottle. As has already been described, the bottom margin 21 of the body portion has a strip of adhesive 23 thereon. This margin is reflexed, that is to say, is bent upwardly within the body portion, as shown more particularly in Figures 7 and 9. The bottom wall 25 has its marginal edge or rim 26 turned downwardly, this rim constituting a flange having a depth preferably equal to the reflexed margin 21 and is positioned between the reflexed margin and the main body portion. The parts will therefore cooperate, one to support the other, and thus provide a substantially rigid bottom edge for the bottle. It is to be understood that the shape of the bottom wall 25 when viewed in plan, has the same shape and external dimension as the internal shape and dimension of the lower part of the body portion of the bottle so there will be a perfect fitting between these parts. The adhesive 23 on the lower section of the body portion will be toward and juxtaposed upon the rim of the bottom wall, and affords a tight sealing for the bottom of the bottle besides retaining the bottom wall from being inadvertently pushed in while in use.

If so desired, the reflexed margin 21 may be

40

corrugated vertically as at 27 or otherwise to both increase its strength and radial pressure outwardly against the rim 26 for a frictional holding contact therewith. The corrugations which consist of alternate grooves and ridges disposed parallel to the axis of the containers may likewise be impressed into the juxtaposed face of the rim 26, if so desired, thereby increasing the security between the parts, frictional expansive contact with the main wall of the container, and strength of the bottom edge of the bottle. The corrugations may even be impressed in the juxtaposed inner face of the main part of the body portion next the outside periphery of the rim 26, all of which is clearly shown in the cross-section of Figure 10. An effective method of assembly of the bottom wall with respect to the side wall of the bottle consists in first corrugating the rim 26 of the bottom wall before insertion of the bottom wall thus corrugated, the bottom margin 21 of the side wall would be reflexed into position and then given a radial or side thrust pressure to unite the parts. This side thrust pressure is preferably accomplished with a corrugating tool by which the reflexed rim will be seated into the corrugations, previously formed, in the rim 26. This method of assembly is distinguished from known previous methods where the bottom edge of the bottles are spun up and over.

I claim:—

A container comprising a body having upper and lower sections, the lower section having a plurality of upright flat sides, and the upper section having a corresponding number of flat sides each of which tapers to a smaller dimension peripherally of the bottle next the top thereof, each of said flat sides being connected by rounded vertical corners.
